UNITED STATES PATENT OFFICE.

EDWIN R. JACKSON, OF OAKLAND, CALIFORNIA.

DESIGN FOR A VAULT-LIGHT.

No. 39,744.

Specification for Design.

Patented Jan. 5, 1909.

Application filed September 11, 1908. Serial No. 452,673. Term of patent 14 years.

To all whom it may concern:

Be it known that I, EDWIN R. JACKSON, residing in the city of Oakland, county of Alameda, and State of California, have invented a new, original, and ornamental Design for a Vault-Light, of which the following is a specification, reference being had to the accompanying drawings, forming part thereof.

Figure 1 is a perspective view of a vault

light, showing my new design. Fig. 2 is a side elevation.

I claim:

The ornamental design for a vaultlight, as shown.

EDWIN R. JACKSON.
